James M. Davis, Jr., P.O. Box 202A, Abilene, Kans.

Filed Feb. 19, 1964, Ser. No. 78,696

Term of patent 14 years

(Cl. D12—2)

FIG. 2

FIG. 1

FIG. 3

FIGURE 1 is an isometric view of a feeding tray for caged animals showing my new design from above and rear, as applied to a wire cage which is fragmentarily shown in broken lines for illustrative purposes only;

FIGURE 2 is a side elevational view thereof on a reduced scale; and,

FIGURE 3 is an isometric view on a further reduced scale taken from below and front thereof.

The fragmentary broken line structure of the cage in FIGURES 1, 2 and 3 is depicted for illustrative purposes only.

I claim:

The ornamental design for a feeding tray for caged animals, substantially as shown and described.
